UNITED STATES PATENT OFFICE.

CHARLES F. MOSMAN, OF BRIDGEPORT, CONNECTICUT.

DESIGN FOR A MIRROR-FRAME.

SPECIFICATION forming part of Design No. 23,654, dated September 25, 1894.

Application filed April 30, 1894. Serial No. 509,590. Term of patent 3½ years.

To all whom it may concern:

Be it known that I, CHARLES F. MOSMAN, a citizen of the United States, residing at Bridgeport, county of Fairfield, and State of Connecticut, have invented and produced a new and original Design for Mirror-Frames, of which the following is a specification, reference being had to the accompanying drawing, showing a part thereof.

- o In the accompanying drawing, the figure is an elevation illustrating my new design for a mirror frame.

The said design consists in its main features of two scroll-like feet 1, 1, with their scrolls turned inward and surmounted by fluted ornaments 2, 2. The central portion of the frame consists of a bead 3, and a series of shell-like ornaments 4 extending from the lower edge thereof and beneath the said shell-like ornaments is a garland 5. Above each

foot of the frame is a shell-like ornament 6 succeeded by three other shell-like ornaments 7, 8 and 9, and between the ornament 6 and the foot is a surface having a floral decoration 10.

The essential features of this design are the succeeding shell-like ornaments at each side gradually diminishing in size, and the central bead with shell like ornaments below the same.

What I claim is—

The design for a mirror frame substantially as herein shown and described.

In testimony whereof I have signed my name to this specification in the presence of 35 two subscriving witnesses.

CHARLES F. MOSMAN.
